UNITED STATES PATENT OFFICE.

JAMES J. DONOVAN, OF BROOKLYN, NEW YORK.

LABEL-AFFIXER.

1,302,142.

Specification of Letters Patent. Patented Apr. 29, 1919.

Application filed July 12, 1916. Serial No. 244,629.

To all whom it may concern:

Be it known that I, JAMES J. DONOVAN, a citizen of the United States, residing at Brooklyn, in the county of Kings and State of New York, have invented new and useful Improvements in Label - Affixers, of which the following is a specification.

This invention relates to the class of label affixers generally and more particularly to that type which are adapted to apply the label to uneven surfaces or over the joints between the several sections of cigarette and tobacco boxes and the like.

While my invention is generally applicable to box making and labeling machines, it is especially adapted for use in connection with those types of machines wherein means are employed for gumming the labels and initially applying the same to the boxes, though I would have it expressly understood that I in no wise, limit myself to such specific application or embodiment of my invention, which I have selected as a basis for illustrating and describing my invention, merely for the purpose of rendering a clear and comprehensible understanding of the scope and novel features thereof.

My invention broadly comprehends the provision or arrangement of elastic means for direct impingement with the box and against the previously gummed and initially applied label, strip of material or otherwise, and a construction of such means which will act to immediately receive the boxes as they are fed from a labeling machine, box making machine or the like or both when used in conjunction with each other, as long as ways are provided for, whereby the labels of the boxes when discharged from such type of machine will be rather moist; said elastic means being universally yieldable and designed so that when engaged with the box or work to be operated upon, its elasticity will be taxed and the same made to adapt itself to any irregularities, inconsistencies of construction or uneven surfaces of the box such as those which are commonly apparent at the joints between the body portions of the boxes and the mating cover sections thereof and thus incident to the taxing of the elas-

ticity of said means to effect a final and perfect application of the labels to the boxes over the mentioned joints and various inconsistencies in the surfaces thereof.

This above described arrangement and functioning becomes necessary where the label constitutes the hinge for the cover section of the box as I have found that many, if not most of the troubles to which such machines are subjected arise through the fact that heretofore, no means are provided to my knowledge, which will automatically conform to the irregularities in the surface of the box and permit of a full application of the label or hinge strip over the joint of the box while the adhesive on the label is in a moist state and at the same time exert a constant pressure against the label for an appreciable length of time.

I shall now proceed to describe one embodiment of the invention with reference to the accompanying drawings, which show a specific application thereof, and then proceed to point out with more particularity, the essential elements of novelty in the annexed claims.

Figure 1 is a view in side elevation of the machine.

Fig. 2 is a top plan view thereof.

Fig. 3 is a section taken on the line 3—3 of Fig. 1.

Fig. 4 is a section taken on the line 4—4 of Fig. 1.

Fig. 5 is a transverse section taken on the line 5—5 of Fig. 1.

Fig. 6 is a section taken through a portion of the machine at the intake end thereof illustrating the box feeding mechanism.

Fig. 7 is a horizontal section showing in detail the application of elastic and expandable conveying and pressing belt.

Fig. 8 is a section taken through portions of two belts showing a slightly modified form thereof.

Fig. 9 is a similar view showing a further modification of the invention.

Fig. 10 is a section through a portion of one of the belts showing its operative application to the box to press the label uniformly in contact therewith over the joint thereof so that the label will constitute a hinge for the cover section of the box.

Fig. 11 is a perspective view of one of the types of boxes intended to be operated upon by the mechanism.

Fig. 12 is a perspective view of the hinge strip label.

In carrying the invention into practice, use is made of a conveyer which is designed to constitute a grasping and pressing means for the boxes and means for arranging the boxes in a continuous row formation. This mechanism consists of an elastic and expandable runway 15, which is defined by endless conveyer belts 16 and 17. These belts are arranged side by side in the same general horizontal line with each other and each consists of inner and outer plies of materials 18 and 19 which are separated from each other relatively by an intervening space 20. In the space 20 is arranged an elastic or expandable core or substance 21 such as sponge-rubber so that the working surfaces of the belts are universally pliable and elastic. Any suitable cushioning agent can, however, be employed in lieu of sponge-rubber without involving departure from my claims. The arrangement is also such that the runway 15 between the belts is elastic or expandable so that when boxes are fed between the belts the elasticity of the latter will be taxed to thereby cause the same to be advanced with pressure against the sides of the box. The arrangement is as though the box to be operated upon was held between the thumb and index finger of the hand and pressure of the fingers exerted against the sides of the box to cause that intimacy of contact between the box and the label or hinge strip that is necessary to effect a uniform contact of the label and permit the latter to adapt itself to all present or existing inequalities in the surface of the box.

These belts are superposed with respect to a supporting frame 22 and as illustrated, such frame includes parallel side bars 23-23 and suitable end members 24 and 25. At the outlet or discharge end 26 of the runway 15, the supporting rolls 27 of the belts 16 and 17, are respectively mounted upon vertical shafts 28 and 29 having their ends mounted in bearings 30 of brackets 31. These brackets are provided with cylindrical portions 32 which are arranged to slide upon rods 33 which are supported in the bracket 25. Set screws or similar retaining devices 34 on the portions 32 are adapted to engage with the mentioned rods 33 so as to hold the rollers 27-27 fixedly spaced apart when the desired adjustment of the runway 15 has been obtained.

At the intake end 35 of the runway, the rollers 36-36 are respectively mounted upon shafts 37 and 38. These shafts are arranged in bearings 39 upon brackets 40-40. These brackets are provided with cylindrical portions 41 which are free to slide on trans-

verse rods 42. Set screws or equivalent fastenings 43 on said portions 41 are adapted to hold the brackets 40-40 in relatively fixed positions. Each of the shafts 37 and 38 is provided with a bevel gear 44 which are arranged in meshing engagement with bevel gears 45 on a power transmitting shaft 46. The gears 45 are adapted to slide upon the shaft 46 when it is desired to change the adjustment of the belts 16 and 17. Ordinarily, they are held fixed upon the shaft by set screws 47.

The shaft 46 is provided with a ratchet wheel 48 which co-acts with a rocking dog 49 which is arranged to be controlled by a link 50, the latter having connection with a crank arm 51 on the shaft 52 of a box feeding mechanism 53. Power is adapted to be transmitted to the shaft 52 by means of a reciprocating bar 54 which may be connected in any suitable well known manner with a box making machine or otherwise.

The box feeding mechanism 53 at the inlet end 35 of the runway 15 comprises the mentioned shaft 52 which is provided with a plurality of lifting fingers 55 which are adapted to be rocked or oscillated when the shaft 52 is in motion. These fingers work between box guides 56 which extend from fixed bracket plates 57. The machine is adapted to be arranged with its intake end in receiving proximity with the discharge end of a box making machine so that the boxes as they are discharged singly from such machine will be deposited upon the fingers 55. In view thereof it is manifest that when the shaft 52 is rocked in one direction, the boxes are adapted to be successively introduced to the runway 15 for direct impingement against the inner leads of the belts 16 and 17.

Supported by the frame 22 are horizontally disposed bars 58 on which are mounted sliding frames 59 which support tensioning rolls 60. These frames are adapted to be moved sidewise relatively of the inner leads of the belts 16 and 17 so that the rolls 60 can be pressed against said leads of the belts and thereby form a relatively fixed backing for said leads in order that the elasticity of the runway will be taxed on the introduction of the boxes thereto. The frames 59 are provided with brackets 61 having elongated slots 62 therein. The bars 58 are provided with set screws 63 which pass through the slots 61 and which are therefore arranged to hold said brackets in fixed positions. The brackets 40-40 are provided with suitable extensions 64 in which tensioning rolls 65 are mounted. These rolls are arranged in the same general line with the rolls 60 and are also adapted to bear against the inner leads of the belts 16 and 17.

The machine herein described is intended to operate upon boxes of the character shown

at 66 in Figs. 10 and 11 wherein use is made of a cover section 67 and a body section 68. It is customary when labeling the boxes to employ what is known as a hinge strip, the same being pasted over the joint between the two sections 67 and 68. This strip is shown at 69 and is adapted to be arranged over one side of the body portion of the box as at 70 and then folded over one of the adjacent sides of the box as at 71, it being understood that the strip 69 has been previously gummed and initially applied to the box before the latter is introduced to the runway 15 and subjected to the action of the belts 16 and 17. After the label is applied and the box conducted to the runway, while in an upright position, the portion 71 of the label or hinge strip is brought to bear against the next adjacent belt and incident to the elastic or expandable action thereof, it will be observed on reference to Fig. 10, that the belt will automatically accommodate itself to those irregularities or inconsistencies in the surface of the box and thereby cause said portion 71 to be uniformly brought into close contact with the companion sections of the box. To my knowledge, this method or arrangement of providing means which is automatically elastic and universally flexible 30 is new in the art. In practice, I find that best results are obtained by initially adjusting the runway so that in width the same is slightly less than the width of the box to be operated upon in that when the box is in position between the inner leads of the respective belts 16 and 17, the elasticity of said leads will be immediately taxed. By backing the inner leads by the rollers 60, sufficient pressure of the leads can be applied 40 against the box to satisfactorily advance the same into close contact with all irregular surfaces.

In the form of runway shown in Fig. 9, I provide belts 70' and 71', the former being formed of a single ply of material and the latter being preferably of the same design as the one previously described herein. It may be preferred to provide the belt 71' with spaced cleats 72 which are designed to engage against the body portions 73 of those forms of boxes in which the cover sections 74 are extended beyond said body portions.

In the form shown in Fig. 8, the belts 75-75 are identical in construction with the preferred embodiment of the invention except that each is provided with spaced cleats 76.

What is claimed as new is:—

1. Mechanism for finishing the application of previously pasted and initially applied hinge strips to boxes comprising, means for grasping the box between a plurality of its sides and for exerting lateral pressure thereagainst to effect a final impingement of a previously gummed strip

thereagainst, said grasping means embodying a lateral elastic member consisting of plies of materials wherein one of said plies is of a different degree of elasticity from the other. 70

2. Mechanism for finishing the application of previously pasted and initially applied hinge strips to boxes comprising, elastic members spaced apart to define an expandable runway therebetween adapted to receive the boxes therein, and means for setting said members in motion to cause the boxes to be conveyed from end to end of the mechanism to the other end thereof while the boxes are in intimate confinement with said members, said members each including a plurality of plies of rubber spaced apart and provided with an intermediate pliable portion having a different degree of elasticity from said plies. 75 80 85

3. Mechanism for finishing the application of previously pasted and initially applied hinge strips to boxes comprising, relatively elastic members arranged side by side to define an intervening space therebetween 90 for the reception of the boxes so that an entrance of the boxes between the members will tax the elasticity of the same, means for causing the boxes to be fed from end to end of said members while in contact therewith, said members embodying belts each having an intermediate portion possessing a different degree of elasticity from the outer faces of the belts. 95

4. Mechanism for finishing the application of previously pasted and initially applied hinge strips to boxes comprising, relatively elastic members arranged side by side to define an intervening space therebetween 100 for the reception of the boxes so that an entrance of the boxes between the members will tax the elasticity of the same, means for causing the boxes to be fed from end to end of said members while in continuous contact therewith, said members each having a plurality of portions respectively possessing different degrees of elasticity. 105 110

5. Mechanism for finishing the application of previously pasted and initially applied hinge strips to boxes comprising, movable members each possessing varying degrees of elasticity spaced apart to define a runway therebetween for the reception of the boxes, means for simultaneously moving both members at the same rate of speed, and 115 means for successively introducing the boxes to the runway to subject the same to the conveying and impinging action of said movable members. 120

6. Mechanism for finishing the application of previously pasted and initially applied hinge strips to boxes comprising, movable elastic members arranged side by side to define an intervening space therebetween 125 for the reception of the boxes so that an 130

- entrance of the boxes in said space will tax the elasticity of the members and cause the same to exert lateral pressure thereagainst, said members each possessing varying degrees of elasticity, means for successively feeding the boxes to said space, and means for operating the members to move the boxes from one end of the space to the other end thereof. 5
- 10 7. Mechanism for finishing the application of previously pasted and initially applied hinge strips to boxes comprising, elastic mechanism for grasping the boxes in line with the joints between the body portions of 15 the boxes and the cover sections, said mechanism having a box receiving end and a discharge end, said mechanism serving to continuously exert pressure against the boxes from the time of its receipt of the box to 20 the time of a discharge of the box from said mechanism, and embodying co-acting members each possessing varying degrees of elasticity.
8. A machine of the class described, mechanism having inlet and discharge ends, and 25 means for conveying boxes from one of such ends to the other and for exerting a continuous lateral pressure thereagainst during the period of progression of the boxes, said 30 conveying means possessing varying degrees of elasticity, as and for the purpose set forth.
9. A machine of the class described comprising, members constituting a laterally 35 expandible runway, means for setting said members in box conveying motion, and means for adjusting said members relatively to vary the width of the runway, said members each comprising an elastic core and a yieldable enveloping means therefor. 40
10. A machine of the class described comprising members constituting a runway, and means for imparting motion to said members, said members each comprising an elastic core and a yieldable enveloping means 45 for said core.
11. A machine of the class described comprising members constituting a runway, and means for imparting motion to said members, said members each comprising an elastic core and a yieldable enveloping means 50 for said core.
12. A machine of the class described comprising members constituting a runway, and means for causing the articles to be moved 55 from one end of said runway to the other end thereof while in contact with said members, one of said members comprising an elastic core and a yieldable enveloping means for said core. 60
13. A machine of the class described comprising members constituting a runway, one of said members being in the form of an endless traveling belt consisting of an inner yieldable core and an outer enveloping covering therefor of yieldable material. 65

In testimony whereof I affix my signature.
JAMES J. DONOVAN.
